UNITED STATES PATENT OFFICE

OTIS E. LAW, OF BROOKFIELD, ILLINOIS, ASSIGNOR TO PINLESS CLOTHES LINE CORPORATION, OF BROOKFIELD, ILLINOIS

METALLIC CLOTHESLINE

Application filed August 21, 1930. Serial No. 476,788.

This invention relates to a metallic clothes line, and an object is the provision of an improved metallic clothes line made up of a plurality of connected sections or links having numerous features of novelty and advantage over previous forms, including durability and efficiency in use, and economy of manufacture. A further object is the provision of a metallic clothes line in which the individual sections are each formed of a single piece of spring metal, and in which the sections are all identical in structure and formation, contributing to the low cost of manufacture. An additional object is the provision of a metallic sectional clothes line dispensing with the necessity of extra hinge or connecting members for the individual sections or links, and arranged to be folded or collapsed into extremely compact form. A further object is the provision of a practically indestructible metallic clothes line in which the sections or links composing the line are conveniently connected or disconnected, and which dispenses with the use of clothes pins or other fastening devices for suspended articles. As a further object in the metallic clothes line of the present invention, no wire ends or rough projections are exposed, upon which articles of fine texture might become torn, but a continuous smooth metal surface is presented in the assembled line.

Other objects will appear hereinafter.

The invention consists in the combinations and arrangements of parts hereinafter described and claimed.

The invention will be best understood by reference to the accompanying drawings, forming a part of this specification, and in which:

Fig. 1 is an elevational view showing a metallic clothes line constructed in accordance with the present invention and erected in operative position;

Fig. 2 is an enlarged plan view of a plurality of connected link sections showing the manner of engagement of clothes or other articles for drying purposes;

Fig. 3 is a plan view of a section, to show the manner of assembly and connection with an adjoining section;

Fig. 4 is a plan view of a detached section of the clothes line; and

Fig. 5 is a view of a plurality of sections in folded or collapsed position.

As illustrated in the drawings, the preferred embodiment of the invention comprises an assembled line 6 as shown in Fig. 1, which may be secured at one end to any suitable support such as a building 7, and at the opposite end to a post 8 by means of hooks 9. Referring to Fig. 4, an individual section comprises a single piece of spring wire, preferably rust-proof in composition, which is bent or formed into distinctive structural formation to compose the side portions 10 and 11, and an intermediate transverse coil portion 12. As shown, side portions 10 and 11 extend longitudinally, and are preferably slightly curved outwardly, and are then bent inwardly to form straight, transverse end portions 13 and 14 which, allowing for the resiliency of the metal used, are adapted to extend substantially parallel to the end coil 12. Each end portion 13 and 14 is preferably of slightly less length than the coil portion 12, and the coil portion 12 is formed of an inside diameter to accommodate the two end portions 13 and 14 in overlapped relation as shown in Fig. 3, when the sections are assembled.

With the construction and arrangement shown, the individual sections may be conveniently assembled by hand to form a composite continuous line, by the mere expediency of giving the side portions 10 and 11 a complete single twist, as shown in Fig. 3, whereupon the end portions 13 and 14 are inserted in the substantially cylindrical coil 12 of an adjoining section, and maintained in engaged position by the resiliency of the spring wire used. Coil 12 is formed to provide an engaging socket for the free ends 13 and 14 of an adjoining section, and also completes a hinge connection between two adjoining sections. Thus an assembled line may be lengthened or shortened by the addition or reduction of sections with the utmost convenience and facility.

Referring to Fig. 2, an article 15 to be suspended for drying is engaged by sliding the

end portions 16 between the overlapping portions of the twisted wire, and the capacity of the line may be practically doubled by suspending articles on the opposite side of the line, such as article 17 with the corner portions 18 engaged at the opposite sides of the twisted portions of the sections. By the elimination of extra connecting members, and by utilizing the wire composing a section to form the connecting hinge 12, the utmost compactness is attained when a plurality of sections are folded or collapsed as shown in Fig. 5.

In commercial manufacture, No. 14 high carbon steel wire has been found highly suitable as possessing adequate strength, resiliency, and lightness without excessive bulkiness.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. A device of the class described comprising a section formed of resilient metal bent to provide two side portions and a connecting end portion, said end portion formed into a cylindrical coil to provide a socket, said side portions twisted to provide an overlapping article engaging portion, and said side portions bent for extension within the cylindrical coil of an adjoining section.

2. A device of the class described comprising a section formed of resilient metal bent to provide two side portions and a connecting end portion, said end portion formed into a cylindrical coil to provide a socket, said side portions twisted to provide an overlapping article engaging portion, and the free ends of said side portions bent substantially parallel to said coil and adapted to be engaged by the coil on an adjoining section.

3. A device of the class described comprising a section formed of resilient metal bent to provide two side portions and a connecting end portion, said end portion formed into a cylindrical coil to provide a socket, said side portions twisted to provide an overlapping article engaging portion, and the free ends of said side portions bent substantially parallel to said coil and adapted to be engaged by the coil on an adjacent section, each of said bent end portions being of less length than the length of said coil.

4. A sectional metallic clothes line comprising a plurality of detachable sections, each section composed of a length of resil-

ient metal bent to provide two longitudinally extending side portions, said side portions twisted to provide an overlapping article engaging portion, a transverse end portion connecting said side portions, said transverse end portion formed into a cylindrical coil to provide a socket, and the free ends of said side portions being bent for engagement by a corresponding cylindrical coil on an adjoining section after said side portions have been twisted.

5. A sectional metallic clothes line comprising a plurality of detachable sections, each section composed of a length of resilient metal bent to provide two longitudinally extending side portions, said side portions twisted to provide an overlapping article engaging portion, a transverse end portion connecting said side portions, said transverse end portion formed into a cylindrical coil to provide a socket, and the free ends of said side portions being bent for engagement by a corresponding cylindrical coil on an adjoining section after said side portions have been twisted, each of said bent end portions being of less length than the length of said coil.

In testimony whereof I have signed my name to this specification.
